CLAIM

The ornamental design for a test reader, as shown and
described.

DESCRIPTION

FIG. 1 is a perspective view of the test reader.

FIG. 2 is a front view of the test reader.

FIG. 3 is a back view of the test reader.

FIG. 4 is a right-side view of the test reader.

FIG. 5 is a left-side view of the test reader.

FIG. 6 is a top view of the test reader.

FIG. 7 is a bottom view of the test reader; and,

FIG. 8 is a perspective view of the test reader in a condition
of use.

In the drawings, the broken lines depict environmental
subject matters and form no part of the claimed design.
